CLAIM

The ornamental design for a microphone or similar article, substantially as shown and described.

DESCRIPTION

FIG. 1 is a top perspective view of a microphone or similar article showing my new design;

FIG. 2 is a side elevation thereof;

FIG. 3 is a bottom plan view thereof;

FIG. 4 is a rear end elevation thereof; and

FIG. 5 is a top perspective view of a modified embodiment of the microphone illustrated in FIG. 1.
